UNITED STATES PATENT OFFICE.

LOUIS CUVELIER, OF HALIFAX, NOVA SCOTIA, CANADA, ASSIGNOR TO EDMUND L. MACDONALD, OF HALIFAX, NOVA SCOTIA, CANADA.

HEEL.

1,197,452.

Specification of Letters Patent.

Patented Sept. 5, 1916.

Application filed October 25, 1915. Serial No. 57,874.

To all whom it may concern:

Be it known that I, LOUIS CUVELIER, a subject of the King of England, residing at Halifax, in the county of Halifax, Province 5 of Nova Scotia, Dominion of Canada, have invented certain new and useful Improvements in Heels; and I do declare the following to be a full, clear, and exact description of the invention, such as will enable others 10 skilled in the art to which it appertains to make and use the same.

This invention relates to new and useful improvements in heels, and more particularly to interchangeable heels for shoes and 15 boots, and the primary object of this invention is to provide an interchangeable heel which may be easily removed and attached and yet will be firmly and securely held in working position.

20 A further object of the invention is to provide a device of this character which is simple and durable in construction, inexpensive to manufacture and one which will be very efficient in operation.

25 With these and numerous other objects in view my invention consists of the novel features of construction, combination and arrangement of parts which will be herein referred to and more particularly pointed 30 out in the specification and claim.

In the accompanying drawings: Figure 1 shows the heel before the new and improved rubber heel is attached thereto; Fig. 2 shows the invention applied; Fig. 3 is a central 35 vertical longitudinal section; Fig. 4 is a transverse section; Fig. 5 is a perspective view of the detachable heel, with the locking means applied thereto; Fig. 6 is a perspective view of the locking means.

40 In describing my invention I shall refer to the drawings in which similar reference characters designate corresponding parts throughout the several views, and in which the numeral 1 designates the heel proper, 45 and the numeral 2 the heel piece which may be formed of rubber, or of any desired material, and which has the heel plate 3 secured thereto. This heel plate 3 which is secured to the heel piece 2 is formed of a metallic 50 plate, the same being dished as shown at 4 and having a centrally disposed slotted aperture 5 therethrough adapted to receive different sized locking members. This aperture 5 is disposed at the lowermost point of 55 the dished plate 3, and is adapted to aline

with a correspondingly shaped aperture 6 which extends through the heel piece 2, for a purpose to be hereinafter more fully set forth. The upper surface of the heel piece 2 is concaved so that it will conform substantially to the dished adjacent side of the 60 heel plate.

The heel plate 3 has its outer edge 7 formed with alternate flanges 8 and spurs 9 on the same. These alternate flanges and 65 spurs are bent oppositely in a plane at right angles to the plane of said plate, and the flanges 8 are apertured as shown at 10, so that when they are embedded in the heel piece 2, when the plate 3 is positioned thereon, will form an additional securing means to hold the plate in said position. When the plate is in the above described position that is superficially arranged on the upper 70 surface of the heel plate 2, the flanges 8 will be firmly and securely embedded into said plate, which will hold the same in position. The spurs 9 being bent in opposite directions from the flanges 8 will extend upwardly, so that when the heel piece is brought 75 into engagement with the heel proper the spurs 9 will be engaged with the lower surface of the heel.

The heel proper has centrally disposed therein an aperture 11, which is adapted to 80 aline with the openings 5 and 6 in the heel plate and heel piece, so that when the two parts of the heel are brought adjacent to each other, a locking member, which comprises in this instance an ordinary wooden 85 screw may be so positioned as to lock these parts into engagement, as clearly shown in Fig. 3 of the drawings.

When the heel plate, and heel proper are 90 positioned as above described, it will be obvious that the upwardly projecting spurs 9 on the plate, will engage the lower surface of the heel proper and penetrate the same, by pressure of the foot, and subsequent 95 tightening of the screw, or by the tightening 100 of the screw only. When these spurs 9 have once penetrated the heel proper they will prevent rotation of the two parts, and if the heel piece becomes worn down at one corner 105 the heels of the right and left shoe may be taken off and changed from one to the other, when the spurs on the same will at once center the heel pieces in their proper place.

From the foregoing description of the 110 construction of my improved interchange-

able heel, the manner of applying the same to use and the operation thereof will be readily understood and it will be seen that I have provided a simple, inexpensive and efficient means for carrying out the objects of this invention.

I claim as my invention:

A heel plate formed of a single piece of flat metal having alternately spaced flanges 10 and spurs on its arcuate edge, and a centrally disposed spur with a pair of adjacent flanges on its straight edge, said plate having its central portion dished and an opening therethrough, the flanges on the edge of said

plate being bent downwardly at right angles 15 to the same, each of said flanges having an opening therethrough, and the spurs on said edge projecting upwardly at right angles to the plate and in a single plane with the downwardly bent flanges.

In testimony whereof I have hereunto set my hand in presence of two subscribing witnesses.

LOUIS CUVELIER.
